240,108

COMBINED FID AND AWL

James D. McGrew, 8120 Rio Linda Blvd.,
Elverta, Calif. 95626

Filed Apr. 3, 1975, Ser. No. 564,610

Term of patent 14 years

Int. Cl. D8—05

U.S. Cl. D8—14

FIG. 1 is an elevational view of one side of a combined fid and awl, showing my new design, the opposite side being in mirror symmetry;

FIG. 2 is an elevational view of one end of FIG. 1, the opposite end being in mirror symmetry;

FIG. 3 is a top plan view of FIG. 1;

FIG. 4 is a bottom plan view of FIG. 1;

FIG. 5 is a median vertical longitudinal sectional view of FIG. 1, the plane of the section being indicated by the line 5—5 in FIG. 4; and

FIG. 6 is an exploded elevational view of one end, as in FIG. 2, showing the fid portion, which lays open a twisted or braided line, separated from the hollow sleeve, which holds the line open while a tuck strand is led

through the sleeve, followed by withdrawal of the sleeve to allow the line to close on the tuck strand.

I claim:

The ornamental design for a combined fid and awl, as shown and described.
